METHOD OF PACKAGING ICE

Maxwell T. Zeigler, Huntington Park, Calif., assignor, by mesne assignments, to Zeigler Packaged Ice Machinery Corporation, Huntington Park, Calif., a corporation of California

Application July 30, 1931, Serial No. 554,141

3 Claims. (Cl. 93—2)

This invention relates to methods of packaging articles, and more especially to a method of wrapping articles composed of frozen material.

One of the objects of the present invention is to provide a method of packaging ice as one of the steps in the preparation of ice for marketing, so that the purchaser of ice receives a dry, easily handled package.

Another object is to provide a method as above described, wherein the steps of cutting the ice into blocks of proper size, wrapping the blocks, and fastening the wrapping material, are all performed within an atmosphere the temperature of which is below the freezing point of the material of which the ice is composed. This insures that the ice being cut and wrapped will be dry, and thereby avoids danger of rusting the cutting and wrapping machinery and of harming the wrapping material by the absorption of moisture.

A further object is to provide a method of wrapping refrigerated articles, which includes the steps of enclosing the article within a suitable wrapping material, fastening the wrapping material by means of a suitable glue, and applying heat to the glued portions to establish a suitable bond between the glued portions before the glue is chilled to such an extent that it loses its adhesive qualities.

The invention possesses other objects and advantageous features, some of which, with those enumerated, will be set forth in the following description of the invention's particular embodiment which is illustrated in the drawing accompanying and forming a part of the specification.

Referring to the drawing:

Fig. 1 is a perspective view of a block of ice during the initial stage of the wrapping operation.

Fig. 2 is a side elevation of a partially wrapped block of ice showing one method of applying glue to one of the flaps of the folded paper.

Fig. 3 is a side elevation illustrating the method of applying heat to the glued portions of the package.

Fig. 4 is a perspective view showing a completed package.

The herein described method of packaging ice and other refrigerated articles has been developed primarily in conjunction with the development of the ice wrapping machine forming the subject matter of my copending application, Serial No. 554,142, filed June 30, 1931, although the present method is also capable of being car-

ried out by means of other machines and manually.

In the preferred method of practicing the present invention, ice is formed into preferably rectangular blocks of predetermined size and weight, this being accomplished either by freezing the material of which the ice is to be composed in molds of suitable shape and capacity, or by cutting larger blocks into blocks of the proper size for marketing, or in any other convenient manner. Each block is then wrapped in a suitable wrapping material, which is then fastened in such a manner that there is no danger that the wrapping material will become dislodged until the ice is desired for use, i. e., until the consumer purposely removes the wrapping. The steps of cutting, wrapping, and fastening are all performed within a suitably refrigerated room or compartment, wherein the atmosphere is maintained at a temperature lower than the freezing point of the material of which the ice is composed, thereby preventing melting of the ice during its preparation for marketing.

Fig. 1 illustrates a block 6 of ice which has previously been formed to the proper shape and size, placed in position upon a sheet 7 of suitable wrapping material in readiness to be wrapped therein. Preferably, the material of the sheet 7 is a suitable wrapping paper—for example, paper of the type known in the trade as "sixty pound craft," this paper being particularly advantageous because of its comparatively great strength and toughness. The sheet 7 and block 6 are disposed upon a suitable support within an atmosphere the temperature of which is below the freezing point of the material of which the ice is composed. In the case of ice made by freezing water, the working temperature at which the present process of packaging is performed is between twenty-five and twenty-eight Fahrenheit degrees above zero. This temperature of the atmosphere within which the packaging process is being performed is maintained in any suitable manner, such as by means of a refrigerating machine, the evaporating coils of which are installed in the room or rooms where the cutting and wrapping take place.

Following placing the block 6 upon the sheet 7 of paper or the like, the sheet is folded up about the sides 8 of the block and the ends 9 and 10 are then folded down upon the top 11 of the block in overlapping relation. The projecting side edges 12 of the paper are then folded in against the ends 13 of the block, forming upper

and lower end flaps 14 and 15 which are then folded downwards and upwards, respectively, against the ends of the block, in the order named. The flaps 14 and 15 at each end of the block are 5 also disposed in overlapping relation, preferably with the upper end of each lower flap 15 lying against the outer surface of the associated upper flap 14, as illustrated upon Fig. 4, which shows the completed package. Preferably, the above 10 described folding operation is performed in the manner, and by the machine, described in my aforesaid copending application.

The folded paper 6 is retained upon the block after completion of the folding operation, preferably by means of a suitable adhesive applied to predetermined portions of the paper. For example, liquefied glue 16 is applied to the under surface of the end 10 of the paper, as indicated at 17, this being the end which is disposed against 15 the outer surface of the other end 9, and also the under surfaces of the lower end flaps 15, as indicated at 18. Whereas any suitable means for applying the glue 16 may be employed, I prefer that a suitable quantity of the liquefied glue 20 be retained within a suitable receptacle 19 adjacent the location at which the wrapping operation is being performed. This receptacle 19 is equipped with an electrical resistance element 20, to which current is supplied by means of conductors 21, so as to keep the supply of glue 16 25 at a higher temperature than the surrounding atmosphere. This has been found to be advantageous, inasmuch as when the liquefied glue is permitted to cool to about the freezing temperature, it tends to lose its liquidity and its adhesive qualities. The glue may be applied to the proper areas of the paper 7 by rollers such as that illustrated at 22. This roller 22 is carried by an arm 23 which is pivotally mounted in such 30 a manner that it may be dipped into the reservoir 19 to moisten the roller, and then raised to such a position that the paper brushes against the roller as the paper is being folded about the block, as illustrated upon Fig. 2.

Upon completion of the folding and gluing operations, I prefer to apply heat to the outside of the package over the areas to which the glue has been applied. This is accomplished by means 35 of presser feet 24, each of which is provided with an electrical resistance 25. These feet 24 are carried by and operated by suitable mechanism (not shown) whereby they are pressed against the outside of the completed package in the proper places. The heat thus applied prevents the glue from being chilled to such an extent that it loses its adhesive qualities before the necessary bond is established between the portions of the paper to be fastened together. However, I have found that the application of heat to the 40 glued portions of the package also expedites the drying of the glue, probably because the heat keeps the glue fluid until it is enabled to penetrate the fibers of the paper, thereby distributing the glue throughout a greater space than it occupied before such penetration, whereby more rapid evaporation of the volatile constituents of the glue is possible. Accordingly, the application of heat to the wrapped package not only facilitates the establishment of the necessary bond between different portions of the folded paper to retain the paper upon the block 6, but it also serves to dry any drops of glue which might be deposited upon the outside of the package and develop the tendency to adhere to neighboring 45

70

packages after delivery from the wrapping machine.

Inasmuch as the present invention contemplates the preparation for marketing of ice for ordinary household use, the material composing the ice is preferably water, although other materials, such as carbon dioxide, may be used. The only change required in the process to accommodate a different material would be that it would be necessary to cool the atmosphere within which 5 the steps of the process are to be performed to a temperature below the freezing point of that material.

The principal advantage of performing the above described steps of my improved method 15 in an atmosphere the temperature of which is below the freezing point of the material frozen to make the ice, is that the ice is prevented from melting during the time at which the process is being performed. Hence, the surface of the 20 block 6 is kept dry, and all dripping of moisture therefrom is prevented. This keeps the cutting and wrapping machinery perfectly dry, even though a large amount of cuttings, chips, and the like are formed by the cutting machine and 25 scattered over both the cutting and wrapping machines. These particles of ice would melt very rapidly owing to their small size were the surrounding atmosphere at a higher temperature, and thus keep the machinery very moist, causing 30 it to rust very rapidly. This is positively prevented, however, by the low temperature which keeps the machinery and the packages themselves perfectly dry.

More important than keeping the machinery 35 dry, however, is the feature of also keeping the wrapped package dry. It has been found to be extremely undesirable to wrap the blocks in an atmosphere above the freezing temperature, because the moisture from the melting ice soon 40 penetrates the fibers of the paper wrapping, thereby reducing its strength and toughness to such an extent that it is practically impossible to handle the package, even to the extent necessary to complete the wrapping operation, without tearing the paper and thus spoiling the package by exposing the ice thereinside.

My process makes it possible to enclose the blocks of ice completely before they are removed from the refrigerated compartment. Hence, the 50 paper wrapping plays an important part in preventing the rapid melting of the ice after it is removed from the compartment by insulating the ice from the warmer atmosphere, which otherwise would engage the ice and instantly start 55 melting it. I have found that the insulating qualities of the type of wrapping material hereinabove set forth are so excellent that the completed package can remain outside the refrigerated compartment for a considerable period of 60 time before the ice melts to any appreciable extent. This permits a purchaser to transport the ice from the place at which it is purchased to a place at a considerable distance therefrom, without losing any appreciable quantity of ice 65 by melting. Moreover, what little moisture is produced by the limited melting of the ice, is confined within the paper wrapping, so that it is much more convenient to handle the package than an unwrapped block of ice, which is very 70 slippery and which is continually dripping.

It is to be understood that the details of the invention as herein disclosed, are subject to alteration within the spirit or scope of the appended claims.

I claim:

1. The method of wrapping ice which consists of placing a block of ice on a sheet of unwater-proofed craft paper in a sub-freezing atmosphere, wrapping the paper about the ice, applying heated adhesive between the layers of the wrapping paper during the wrapping, and applying heat and pressure to the portions of the wrapping paper to which the adhesive has been applied so as to deliver a sealed, wrapped package.
- 5 2. The method of wrapping ice which consists of placing a block of ice on a sheet of paper, wrapping the paper about the ice in a sub-freezing atmosphere, applying heated adhesive between overlapped layers of the wrapping paper
- 10 15

during the wrapping, and applying heat and pressure to the outside of the package over the areas to which the heated adhesive has been applied, and thus delivering a sealed, wrapped package.

3. The method of wrapping ice which consists of placing a block of ice on a sheet of unwater-proofed craft paper in a sub-freezing atmosphere, wrapping the paper about the ice, applying heated adhesive between overlapped layers of the wrapping paper during the wrapping, 10 and temporarily applying heat and pressure to the outside of the package over the areas to which the heated adhesive has been applied, and thus delivering a sealed, wrapped package.

MAXWELL T. ZEIGLER. 15
